ALLAN B. FIELD, OF PITTSBURGH, PENNSYLVANIA, ASSIGNOR TO WESTINGHOUSE ELECTRIC AND MANUFACTURING COMPANY, A CORPORATION OF PENNSYLVANIA.

COIL-WEDGE.

1,150,022.

Specification of Letters Patent. Patented Aug. 17, 1915.

Application filed August 2, 1913. Serial No. 782,566.

To all whom it may concern:

Be it known that I, ALLAN B. FIELD, a subject of the King of England, and a resident of Pittsburgh, in the county of Allegheny and State of Pennsylvania, have invented a new and useful Improvement in Coil-Wedges, of which the following is a specification.

My invention relates to dynamo-electric machines, and it has special reference to coil-retaining wedges adapted for use in such machines.

The object of my invention is to provide a device of the above-indicated character which shall be inexpensive and simple to manufacture, rugged, compact and convenient in construction, and which shall secure for the machine in which it is embodied, the well-known advantages of partially closed slots.

As is well understood by those skilled in the art, in the cores of dynamo-electric machines it is desirable to obtain at the air gap an approximately unbroken area of magnetizable material to effect a uniform distribution of the flux and decrease the leakage thereof, and to reduce the reluctance of the air gap. At the same time, the advantages of the open slot, as regards convenience and the saving in time and labor while assembling the coils on the core, are too obvious to require pointing out. Hence arises the more or less common expedient of employing coil-retaining wedges that embody magnetizable material. For mechanical and magnetic reasons, the outer sheath must be very thin in order to permit the wedge to be securely held in position by the small grooves which are usually provided in the teeth of open-slot machines, and in order to minimize the length of the magnetic circuits.

In the prior art, many coil-retaining wedges have been devised, all of which have been subject to one or both of the following defects: A continuous metal envelop or sheath for the wedge has been employed, thereby, as it were, short-circuiting the laminations of the core and decreasing their effectiveness in preventing losses from eddy currents, or the wedging means has comprised several separate, or more or less unstably assembled, magnetizable and associated insulating portions.

According to my present invention, I pro-

vide a unitary wedge that is adapted to fit in the usual grooves in the core teeth and that comprises a plurality of suitable magnetizable members spaced apart by an insulating member and a thin envelop of a suitable hard insulating material, such as bakelite paper or the like, which products are deemed sufficiently well known in the art to make description thereof unnecessary.

By reason of the construction just described, a strong, compact and convenient wedging member is obtained which secures to the machine employing it the above-mentioned advantages of partially closed slots without embodying either of the disadvantageous features of the prior art hereinbefore pointed out.

In the accompanying drawing Figure 1 is a view in section of a portion of the core of a dynamo-electric machine embodying my invention and Fig. 2 is a view, in perspective, of a wedge with parts broken away to show the details.

Referring to the drawing, a section of a core 1 of a dynamo-electric machine is provided with the usual teeth 2 and with substantially parallel-sided slots 3 in which a plurality of coils 4 are disposed in any well-known fashion. The teeth 2 are severally provided on both sides near their free ends with grooves 5, as is more or less customary. A plurality of unitary wedges 6 are severally disposed in confronting grooves 5 of adjacent teeth 2 to retain the coils 4 in position.

The wedges 6 severally comprise a plurality of magnetizable members 7, an intermediate spacing member 8 and a thin enveloping member 9. The magnetizable members 7 severally constitute bundles of iron wires to reduce internal eddy current losses and are disposed directly within the edges of the thin enveloping member 9, thereby securing, as nearly as possible, the effect of a partially closed slot, and, at the same time, insulating the core 1 from the members 7, for reasons hereinbefore specified. The spacing member 8 is disposed intermediate the two magnetizable members 7 and is of a preferably inherently rigid insulating material, such as bakelite board. The member 9 closely envelops the members 7 and 8 and is of a preferably resinous and hard insulating material, such as bakelite paper.

The method of making the wedges 6 is as follows: A plurality of bundles of the iron wires 7 are inserted within the edges of the previously flattened bakelite or similar tube 9 of any suitable length, and the spacing member 8 is disposed intermediate the members 7. The assembled body is then thoroughly impregnated with bakelite or other suitable insulating fluid and pressed in a mold to a predetermined shape and hardness. The finished wedge 6 is thus sufficiently strong mechanically and the enveloping member 9 is not thick enough to seriously interfere with the magnetic functions of the magnetizable members 7.

I do not wish to be restricted to the specific structural details herein set forth, but desire that only such limitations shall be imposed as are indicated in the appended 20 claims.

I claim as my invention:

1. The method of making a coil-retaining wedge for open-slot dynamo-electric machines that consists in flattening an insulating tube, disposing therein a plurality of magnetizable members, disposing insulating material intermediate said members and pressing the assembled body to a predetermined shape.
2. The method of making a coil-retaining wedge for open-slot dynamo-electric machine that consists in flattening a tube of resinous insulating material, inserting therein a plurality of divided magnetizable members, inserting insulating material intermediate said members, treating the assem-

bled body with an insulating fluid, and pressing the said body to a predetermined shape.

3. The method of making a coil-retaining wedge for open-slot dynamo-electric machines that consists in flattening a tube of resinous insulating material, inserting therein a plurality of stranded magnetizable members, inserting inherently rigid insulating material intermediate said members, impregnating the assembled body with an insulating fluid, and pressing the said body to a predetermined shape and hardness.

4. A coil-retaining wedge for open-slot 50 dynamo-electric machines comprising a plurality of magnetizable members, an intermediate insulating member and an enveloping insulating member, said members being impregnated with an insulating fluid and 55 pressed to form a unified body.

5. A coil-retaining wedge for open-slot dynamo-electric machines comprising a plurality of stranded magnetizable members, an intermediate rigid insulating member 60 and an enveloping member of hard insulating material, said members being impregnated with an insulating fluid and pressed to form a unified body.

In testimony whereof, I have hereunto 65 subscribed my name this 26th day of July 1913.

ALLAN B. FIELD.
